[57] ABSTRACT

A vacuum sheet stripping device is herein disclosed suitable for removing cut sheets of final support material from the surface of an image retaining member, as for example, a xerographic plate, and advancing the separated sheet along a predetermined path of travel.

FIG. 5

FIG. 6

VACUUM SHEET STRIPPING APPARATUS

This invention relates to a vacuum sheet stripping apparatus and, in particular, to apparatus for separating a sheet of final support material from a xerographic plate.

More specifically, this invention relates to a sheet stripping device suitable for use in an automatic xerographic reproducing machine. In the art of xerography, as originally disclosed by Carlson in U.S. Pat. No. 2,287,691, a xerographic plate, generally formed of a photoconductive layer is placed upon a conductive backing, is charged uniformly and the charged plate surface then exposed to a light image of an original to be reproduced. Under the influence of the light image, the photoreceptor is caused to become conductive in the light struck regions so as to selectively dissipate the electrostatic charge thereon. As a result, the original input scene information is recorded on the plate in the form of a latent electrostatic image. The latent image is then made visible by contacting the image bearing plate surface with oppositely charged toner particles which have been specifically developed for this purpose. In general, the oppositely charged toner particles coming in contact with the plate are electrostatically attracted into the charged imaged regions in proportion to the amount of charge present so that the more highly charged regions on the plate are developed as relatively dense toner images while the weakly charged regions are developed as proportionally less dense images.

The developed input scene information recorded on the plate is conventionally transferred electrostatically from the xerographic plate to a final support sheet, such as paper or the like, and the image affixed thereto to create a record of the original. Electrostatic transfer can take many forms but the most widely accepted method in use today is that which was originally disclosed by Schaffert in U.S. Pat. No. 2,576,047. In this particular method, a sheet of insulating support material is placed directly upon the plate surface with one side of the copy sheet in contact with a developed toner image supported thereon. The back of the support sheet is treated with a corona discharge to induce a charge in or on the sheet that is capable of overcoming the forces holding the toner to the plate and electrostatically bonding the toner particles to the sheet in image configuration.

Removal of the support sheet from the image bearing plate surface has long been a problem in the art because of the delicate nature of the finely divided toner image. Prior to fixing, the toner image is loosely adhered to the support sheet and, as such, can be readily disturbed or degraded when contacted in any manner by sheet handling means or the like.

It is therefore an object of the present invention to provide apparatus for removing sheet material from a support surface without engaging the sheet with mechanical grippers and the like.

It is a further object of this invention to separate a sheet of final support material, having a toner image loosely adhering thereto, from a sheet support surface without disturbing the image thereon.

These and other objects of the present invention are attained by means of a sheet stripping device suitable for use in a xerographic reproducing machine having a vacuum drawing means positioned in fluid flow communication with the copy sheet capable of producing

a flow of aeroform fluid over the back side sheet so as to generate an aerodynamic lift sufficient to elevate at least a portion of the sheet above the plate, and further means to direct the lifted portion of the sheet along a predetermined path of travel into a subsequent processing station.

For a better understanding of these and other objects of the present invention, reference is had to the following detailed description of the invention to be read in connection with the accompanying drawings wherein:

FIG. 1 is a schematic diagram of an automatic xerographic reproducing machine embodying the teachings of the present invention;

FIG. 2 is a partial view in section showing the construction of the vacuum housing and associated drive mechanism for removing a sheet of final support material from the photoreceptor of the machine illustrated in FIG. 1;

FIGS. 3-6 are partial section views taken along line 2-2 in FIG. 2 showing the internal construction of the vacuum housing and illustrating the steps involved in removing final support sheet from the photoreceptor and forwarding the sheet to a subsequent processing station;

FIG. 7 is a partial sectional view of the photoreceptor and the vacuum roll illustrating the mechanism for aerodynamically lifting the leading edge of the sheet from the photoreceptor surface.

The apparatus of the present invention is shown in FIG. 1 embodied in an automatic xerographic reproducing machine having a xerographic drum 10 formed of a photoconductive surface 11 placed upon a conductive backing 12. The drum is supported upon a shaft 13 and arranged to pass sequentially through a series of processing stations as it is moved in the direction indicated.

For the purposes of the present disclosure, the several processing stations in the path of movement of the drum may be described as follows:

40 A charging station A, containing a corona generating device 16 being arranged to place a uniform electrostatic charge upon the photoconductive layer of the xerographic drum;

45 An exposure station B, wherein a flowing light image of an original supported upon platen 17 is projected onto the moving drum surface to selectively dissipate the uniform charge found thereon thus recording the original input scene information on the photoconductor in the form of a latent electrostatic image;

50 A developing station C, including a housing 20 containing a quantity of two component developer material and a conveying means 21 adapted to cascade the two component developer material over the electrostatic image bearing plate surface whereby toner particles are attracted into the recorded imaged areas thus rendering the images visible;

55 A transfer station D, wherein the visible toner image supported on the photoconductive drum surface is transferred from the photoconductor to a sheet of final support material and the sheet then forwarded to a subsequent fusing device 23 wherein the images are permanently affixed to the support sheet; and

60 A cleaning station E, in which is located a precleaned corotron 25 for negating any residual charge remaining on the drum surface after the image has been transferred and a housing 26 in which is supported a cleaning member for removing residual toner particles left

on the drum after the completion of the transfer operation.

A sheet registering and forwarding mechanism 30 is positioned at the entrance of the transfer station D. The mechanism is arranged to accept individual sheets of final support material from either of two supply trays 31 and 32. In operation, a sheet feeding means 33, associated with each of the supply trays, separates the topmost sheet from a preselected stack and advances the sheet into the registering and forwarding mechanism. Here the leading edge of the sheet is properly registered in relation with the toner image leaving developing station C so that the sheet is advanced into moving contact with the rotating drum surface with one side of the sheet superimposed over the toner image.

The copy sheet and the toner image are advanced in contact together under a pair of parallel aligned corona generators which extend longitudinally across the photoconductive drum surface. The two corona generators include a first transfer corotron 34 and a second detacking corotron 35. It is herein contemplated, as is conventional in the xerographic process, that a positively charged latent image is recorded on the photoconductive plate and the image is made visible by applying a negatively charged toner material thereto. Transfer corotron 34 is arranged to spray the back side of the copy sheet with a highly positive corona discharge. The charge induced by the transfer generator in or on those regions of the copy sheet overlying the toner image serves to pull the toner particles away from the photoconductive plate surface and to electrostatically bond the toner particles in image configurations upon the contacting side of the copy sheet. However, the charge induced in or on those regions located opposite the non-imaged portion of the photoreceptor, that is, those areas on the photoconductive surface containing no image information and therefore containing no toner thereon, tend to migrate close to the plate surface and, in turn, induces a negative charge in the photoreceptor. Consequently, a relatively strong attracting force is established between the copy sheet and the drum in the non-imaged plate regions which serves to electrostatically tack the copy sheet to the drum. For further information concerning this phenomena reference is had to Dessauer and Clark's text entitled "Xerography and Related Processes" beginning at page 391.

The second corona generating device 35 is also positioned within the transfer station opposite generator 34. Generator 35 is a detacking corotron which is adapted to reduce and/or substantially neutralize the electrostatic bond established between the final support sheet and the photoconductive plate. Detacking of the sheet is accomplished by inducing a second charge in the copy sheet which is capable of counteracting the electrostatic holding forces created during the transfer operation. Corona generator 35 can be of any type capable of attaining this end, however, it is preferred that the detacking corotron be an AC corona generator adapted to produce emissions sufficient to considerably reduce the bond holding the sheet to the photoconductive surface but insufficient to repel the already transferred toner image back toward the photoreceptor surface. For further information concerning this type of corona generating device, reference is had to the heretofore mentioned U.S. Pat. No. 3,357,400.

In operation, the photoconductive drum surface is initially charged at station A to a potential of between +700 and +1,000 volts using a corona generator similar to that disclosed by Vyverberg in U.S. Pat. No. 2,836,725 and which operates in a range of between 8.0 micro amps/in. and 13.5 micro amps/in. The operating range of the generator is determined by placing a grounded electrode at the normal drum position beneath the generator and measuring the current flow between the electrode and ground when the device is operating under normal conditions. Upon completion of the exposure and developing steps, the toner image is transferred to a paper support by means of transfer corotron 34. The transfer generator is supported at about 0.25 inches above the photoconductive surface and draws a current of approximately 8.0 micro amps/in. of wire. Detacking of the copy sheet is accomplished by means of AC generator 35 that operates in a range of between AC 2.75 to 4.50 micro amps/in. and DC +0.30 to +0.80 micro amps/in. plate current.

Positioned downstream in the direction of drum rotation from the AC detacking corotron is a stationary vacuum manifold housing 36 adapted to partially enclose a rotatable pickup roll member 39. The exposed portion of the pickup roll, that is, that portion of the roll extending exterior the housing, is supported in non-contiguous relation above the rotating xerographic drum surface, preferably between 0.25 and 0.30 inches above the photoreceptor surface so that the sheets of support material moving in contact with the plate surface passes under the roll in an uninterrupted manner.

The cylindrical vacuum pickup roll member is rotatably supported between the two end walls 47, 51 of the vacuum housing as illustrated in FIG. 2. The roll basically consists of a tubular hollow sleeve 40 containing a series of longitudinally aligned pickup slots 62 and a number of parallel aligned circumferential slots 63 formulated therein. One end of the sleeve, the left hand end as viewed in FIG. 2, is sealed by means of an end cap 43 while the opposite end of the sleeve is placed in fluid flow communication with a vacuum source (not shown) via a vacuum connector 48 and a hose 66. Circumferential seals 42 and 59 (FIG. 2), as well as drag seals 68 and 69 (FIG. 3), are placed between the housing walls and the roll surface. The seals serve to isolate the interior of the housing from the surrounding atmosphere.

End cap 43 carries a stub shaft 41 therein and the shaft, in turn, is journaled for rotation in the left hand wall of the vacuum housing by means of bearing 45. Vacuum connector 48 is made up of two cooperating hollow elements including a fixed member 65 locked to the right hand end wall of the housing, and a movable member 64 press fitted into the left hand end of the pickup roll sleeve 40. The two cooperating members are movably connected by means of a bearing 45 contained within bearing housing 55 thus allowing the pickup roll to freely rotate about its axial centerline. A gear 55 is machined in the movable member 64 and the gear arranged to mesh with a drive pinion 53 secured to intermediate shaft 54. A drive sprocket 56 is also affixed to the right hand end of the intermediate shaft and is operatively connected to the main machine drive system by means of a timing belt (not shown). The surface speed of the vacuum pickup roll is coordinated through the drive system with that of the rotating xerographic drum surface so that the xerographic drum and

the pickup roll move through pickup zone 71 (FIG. 3) at the same relative speed. As will be explained in greater detail below, the vacuum slots associated with the pickup roll are also arranged to move in relation with the copy sheet to effect the desired sheet removal.

As shown in FIGS. 3-6, an internal seal 67, which extends across the top interior portion of the vacuum housing, is arranged to cooperate with the rotating pickup roll to divide the interior of the housing into two discrete chambers, a first manifold chamber 76 and a second sealed chamber 38 which is totally isolated from the surrounding atmosphere. Just prior to the introduction of a copy sheet 70 into the sheet removal zone 71, both the longitudinally aligned slots 62 and the circumferential slots 63 formed in the pickup roll surface are positioned within the sealed chamber 38. The vacuum being drawn through the pickup roll therefore acts against the closed region between seals 67 and 68 and, as a consequence, a maximum head pressure is developed within the system just prior to moving the pickup openings into the sheet liftoff region.

Further rotation of the pickup roll surface carries the longitudinally aligned pickup openings 62 from beneath the drag seal 68 and positions the slots in non-contiguous relation just behind the leading edge of the copy sheet 70 which, simultaneously therewith, has been advanced into the pickup zone 71 to a position as illustrated in FIG. 4. Because of the pressure difference created between the interior of the pickup roll and the surrounding atmosphere, air is drawn at a relatively high velocity through the pickup slots as the slots are opened to the atmosphere. This flow of air, due to the positioning of the pickup slots, is felt upon the back side of the copy sheet and creates an aero-dynamic lifting force in accordance with Bernoulli's principle which is sufficient to raise at least the leading edge portion of the copy sheet from the photoconductive surface and raise the sheet towards the pickup roll.

The aerodynamic lift is considerably enhanced by reducing or neutralizing the electrostatic tacking forces involved in the manner previously described. Because of its natural beam strength, the leading edge of the detacked support sheet does not conform to the arcuate shape of the drum surface but rather tends to assume a relative straight position as illustrated in FIG. 7. Some finite length of the sheet, a distance designated (x) in FIG. 7, extends outwardly in a beam-like manner from the arcuate drum surface. The length of the beam created is dependent on a number of factors which include the amount of toner present between the copy sheet and the photoconductive surface, the inherent strength of the final support sheet, and the amount of residual electrostatic tacking force acting upon the sheet after the detacking process is completed. In practice, it has been found that a sheet of paper, which has been detacked in the manner herein described, can be efficiently removed from the photoconductive surface by employing an average vacuum pressure at the pickup slots of somewhere between 1.10 and 1.70 inches of water when the pickup slots are supported at approximately 0.030 inches above the back side of the support sheet.

Under the influence of the vacuum pressure the freed leading edge of the sheet is drawn upwardly into contact with the surface of the pickup roll closing the longitudinal pickup slots and securing the sheet to the moving roll surface. As illustrated in FIG. 5, further ro-

tation of the roll in the direction indicated causes the trailing or body portion of the sheet to be pulled or stripped from the drum surface. Simultaneously therewith, the circumferential slots 63 are carried forward from beneath the drag seal 68 and are positioned in fluid flow communication with the back side of the stripped portion of the copy sheet. The negative vacuum pressure created within the pickup roll pulls the body of the copy sheet against the roll at least partially closing the slots 63 and thus securing the trailing portion of the sheet in contact with the roll surface.

Further rotation of the roll results in the leading edge of the sheet being pushed over a series of stripper fingers 60 that are secured to the bottom wall 75 of the stationary manifold 74 thereby separating the sheet from the rotating pickup roll surface. The stripper fingers 71 are generally arranged tangentially to the exterior surface of the cylindrical pickup roll and coact therewith to describe a relatively straight path of travel along which the sheets are guided into a fuser assembly 23. As the support sheet is driven over the stripper fingers toward the fuser assembly, the longitudinal pickup slots 62 are carried beneath seal 69 and are brought within the vacuum housing into manifold chamber 74. As a result, the leading edge of the sheet is released and the manifold region is evacuated causing a negative pressure to be felt at a series of vacuum ports 76 located along the bottom wall 72 of the manifold. The bottom wall of the manifold is arranged at a slight angle in relation to the plane determined by the stripper fingers in order to prevent the copy sheet from completely closing ports 76 and thus preventing an excessive drag from being exerted on the sheet. In practice, the system is designed so that the frictional forces between the surface of the pickup roll and the support sheet, drawn in contact therewith, is always greater than the vacuum forces exerted upon the sheet as it moves along the bottom wall of the manifold. By maintaining this force differential, a sheet of support material can be efficiently pushed along the stationary transport without danger of the sheet being damaged due to wrinkling or buckling.

As shown in FIG. 6, the circumferential slots 63 are arranged to follow the longitudinal slots 62 into the manifold area 74 and continues to hold the interior of the manifold chamber at a negative pressure. During this period, the leading edge of the sheet has traversed the stationary bottom wall of the manifold and moved into the nip between the cooperating fuser rolls 80 and 81. In operation, the fuser rolls are arranged to move at the same peripheral speed as the surface speed of the moving sheet. The fuser rolls are adapted in a manner well known in the art to engage the copy sheet in pressure driving contact and herein function to pull the sheet over the stationary wall after the trailing portion of the sheet is released by the circumferential slots as they are withdrawn within the vacuum housing. As the sheet passes through the nip between the fuser rolls, sufficient heat energy is transferred to the copy sheet to affix the image thereto.

It should be clear to one skilled in the art that the direction and control of the air flow through the present apparatus is determined by the positioning of the vacuum seal within the assembly. Preferably the seals are positioned so as to provide a continuous vacuum acting upon the copy sheet as the sheet is moving between the sheet detacking region and the fusing region. Furthermore, by properly choosing values for the roll diameter

and vacuum slot dimensions, the assembly can be made self-sealing so that a vacuum pressure is only exerted in the pickup region when a sheet of final support material is present therein. During the time that the pickup roll is over an interdocument region, that is, a drum region containing no input scene information, all the vacuum pressure within the system is directed interior the pickup housing thus preventing the unwanted broadcasting of toner throughout the machine.

For purposes of explanatory convenience, references are made throughout the disclosure to negatively charged toner particles as being used to develop a positively charged latent electrostatic image. It should be understood, however, that the polarity of the charges involved is not intended to limit this disclosure and the polarity of the charges can be altered so long as the specific charge relationships remain constant. All references to positive or negative charges therefore can be considered as defining a relationship. For example, a charged body may be positive or negative so long as the relationship of other like or dissimilar charged bodies is maintained.

While this invention has been disclosed with reference to the structure described herein, it is not necessarily confined to the details as set forth and this application is meant to cover all modifications or changes that may come within the scope of the following claims.

What is claimed is:

1. Apparatus for removing a sheet of final support material from the surface of a moving image retaining member, including

a stationary housing being arranged to substantially enclose, in air-tight relationship therewith, a rotatably mounted hollow cylinder having a line of longitudinally aligned vacuum ports therein, said housing having an elongated opening positioned adjacent the image retaining member,

means to rotate said cylinder through an endless path of travel whereby the longitudinally aligned pickup ports pass sequentially through the air-tight enclosed housing and then through the opening therein in close, non-contiguous, relation with a sheet of material supported on the image retaining member,

means to coordinate the movement of the cylinder with the movement of the image retaining member so that the longitudinally aligned vacuum ports are brought into the housing opening over the leading edge of a support sheet transported on the image retaining member, and

vacuum means operatively associated with said cylinder to draw a flow of air through said ports when said ports are positioned in said housing opening to move a sufficient amount of air over the leading edge of said support sheet to raise the leading edge of the support sheet from the image retaining member into holding contact against said vacuum ports.

2. The apparatus of claim 13 wherein said cylinder has at least one other secondary opening therein posi-

tioned behind said longitudinally aligned vacuum ports in relation to the direction of cylinder movement, said second openings being arranged to engage the trailing portion of said sheet, behind the leading edge thereof, in vacuum holding contact with said cylinder as the leading edge portion of said sheet is carried forward by said cylinder.

3. The apparatus of claim 14 further including stripping means positioned between said stationary housing and said moving cylinder which is arranged to move between the surface of said cylinder and the support sheet held in contact therewith so as to redirect said sheet away from said cylinder.

4. The apparatus of claim 15 wherein one wall of said stationary housing includes an extended surface adapted to co-act with said stripping means to redirect the support sheet along a predetermined path of travel.

5. Apparatus for removing a sheet of final support material from the surface of a moving image retaining member including

a rotatable hollow cylinder having a series of ports therein,

vacuum drawing means operatively associated with the rotatable hollow cylinder for developing negative pressure at said ports,

means to rotate said cylinder whereby the ports are transported sequentially through a series of stations including

a first station having means to seal said ports whereby a maximum negative pressure is developed at said ports,

a second pick up station in which said ports are brought into close non-contiguous moving relation with the leading edge of the sheet of support material on the surface of the image retaining member whereby a flow of air is caused to move over the back of the sheet as the air is drawn through said ports to lift the leading edge of said sheet into holding contact against said cylinder, and

a third sheet stripping station comprising an enclosed vacuum chamber through which said ports are passed, said chamber having one stationary wall cooperating with the rotating cylinder to strip the sheet from the cylinder and guide the sheet along a predetermined path of travel, said wall further having an opening for placing the sheet in fluid flow communication with the vacuum chamber whereby the sheet is held in sliding contact with the wall when said vacuum ports are positioned within the chamber.

6. The apparatus of claim 10 wherein the peripheral speed of said cylinder is substantially equal to the speed of movement of the image retaining member.

7. The apparatus of claim 11 having further sheet guide means arranged to cooperate with said cylinder to redirect the stripped portion of said sheet along a predetermined path of travel.
